UNITED STATES PATENT OFFICE.

GEORGES J. N. CARPENTIER, OF WASHINGTON, DISTRICT OF COLUMBIA.

TORPEDO.

1,290,829.

Specification of Letters Patent.

Patented Jan. 7, 1919.

Application filed October 20, 1917. Serial No. 197,632.

To all whom it may concern:

Be it known that I, GEORGES J. N. CARPENTIER, a citizen of the United States, residing at Washington, in the District of Columbia, have invented certain new and useful Improvements in Torpedoes, of which the following is a specification.

This invention relates to torpedoes, and more particularly to attachments for submarine torpedoes whereby the same may be conveniently and practically launched from aeroplanes or the like.

One of the objects of the present invention is to provide a means or an attachment to convert an ordinary submarine torpedo for the above usage, which alteration or attachment may be easily and quickly accomplished. A further object is to provide an attachment of the above general character which will be reliable and efficient in use and operation. A further object is to provide an attachment of the above general character having relatively few parts which may be inexpensively manufactured and easily installed. A further object is to provide means for affecting the center of gravity of a torpedo before and after launching.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same into the numerous modifications in structure and relation contemplated by this invention, drawings depicting a preferred form have been annexed as a part of this disclosure, and in such drawings, like characters of reference denote corresponding parts throughout all the views, of which:

Figure 1 is a semi-diagrammatic view showing the manner in which a torpedo may be launched from an aeroplane, and its course toward the target after launching.

Fig. 2 is an elevational view of the forward part of an ordinary submarine torpedo with the attachment applied thereto.

Fig. 3 is an enlarged detail view taken on the line 3-3, Fig. 2.

Fig. 4 is a detail sectional view taken longitudinally and centrally of the forward part of the torpedo with the attachment applied thereto.

60

Fig. 5 is a front elevational view.

65

Referring now in detail to the drawings, and more particularly Fig. 1, 5 indicates diagrammatically an aeroplane, or the like, traveling above the water toward the target, indicated by the sectional view of a boat 6. The aeroplane has launched a torpedo 7, which owing to the speed of the aeroplane will follow a trajectory substantially along the line indicated at 8. This line will vary 70 with the speed and elevation of the aeroplane and may be easily calculated by reference to instruments carried thereby. After submergence, an attachment indicated at 10, automatically separates from the torpedo 7, as indicated, after which the torpedo will pursue its intended course toward the target 6.

75

In order that the objects sought to be obtained by the present invention may be more clearly understood, it may be noted that torpedoes of the submarine type now in general use have a center of gravity very closely coincident with the actual center. Thus, if an ordinary torpedo is dropped or launched 80 from an aeroplane at a distance or elevation greater than fifteen feet, there will be a tendency for such torpedo to turn over with respect to its transverse axis and land in a haphazard position in the water. Its future 85 course under those conditions cannot, of course, be foreseen. The present invention is therefore directed to overcoming this objection by applying suitable means, such as a false nose or head, to the torpedo whereby 90 its center of gravity will be shifted forwardly of the actual center, and also at a point considerably lower than the central horizontal plane. Thus as the torpedo is launched, it will tend to follow its trajectory 100 without turning on its transverse axis, or longitudinal axis, and will land in the water in approximately such desired position as will enable it to free its false nose and then continue toward the target under its own 105 propelling means, as intended.

The attachment hereinafter described will automatically shift the center of gravity of the torpedo to the desired location with respect to its actual center to accomplish the 110 desired launching in a practical and efficient manner, and after launching to auto-

matically restore the center of gravity whereby it may continue its way as intended.

In order to accomplish these objects, there is provided at the forward end of the torpedo 5 a hollow cap 11, Fig. 2, of substantially semi-spherical internal construction, or such other construction as will substantially conform to the actual shape of the torpedo heads now in general use. This cap is secured to the body of the torpedo in any desire manner, but preferably by the use of a plurality of longitudinal strips 12 of any suitable material having a relatively high tensile strength under normal conditions 15 but adapted to lose such tensile strength immediately upon submengence. Ordinary blotting paper, for example, which may be considered a semi-soluble fibrous material, will comply with such requirements and is 20 found to be exceedingly cheap and practical. Around the ends of these longitudinal strips 12 there is provided a fastening means which may be of the same or similar material in the form of a tape 13 adapted to be wound 25 a plurality of times around the cap 11 at the point or junction between the cap and the longitudinal strips 13. A second strip of tape 14 is also wound around opposite ends of the longitudinal strips 12 and their point 30 of attachment to the body of the torpedo 7.

After these parts are assembled, a shield 15 of any desired length sufficient to protect the internal mechanism is secured to the under side of the body of the torpedo and 35 is held in place by means of a relatively broad strip 16 of paper or other suitable material answering the requirements above set forth. The shield is preferably of such shape as to fit snugly to the under side of the body of the torpedo, and in the illustration shown in the drawing is substantially U-shape in cross-section. The forward end of this shield is rigidly secured by means of bolts 17 to the under side of the cap. The 40 cap and shield together weigh approximately one-hundred pounds, and it will thus be seen that in a torpedo weighing approximately ten or twelve-hundred pounds, the center of gravity will be shifted relatively 45 forwardly and downwardly to an extent sufficient to permit the launching of the torpedo from the aeroplane with the assurance that such torpedo will follow a true trajectory into the water without turning.

50 In order to insure the complete severance of the surrounding tapes 13 and 14, there is provided on the under side of the torpedo a block 18 having a longitudinal groove in which slides a knife or cutting tool 20 adapted to be actuated by means of a cord or wire 21 secured in any convenient part of the forward end of the nose or shield. When the torpedo is submenged, the longitudinal strips 12 break and the tapes 13 and 14 55 loosen, permitting the cap to fall away from

the torpedo, drawing the knife 20 longitudinally along its slide thereby cutting the tapes on the under side of the torpedo where they are more or less protected from the action of the water and insuring the complete severance of the cap. 70

It is believed that the method of use and operation of a device of this character will be clear to those skilled in the art. It is sufficient to state that the torpedo is preferably carried between the pontoons of a hydroplane with its longitudinal axis coincident with the normal direction of flight of the hydroplane. Any suitable form of releasing means may be employed adapted to 75 drop the torpedo instantly at both forward and rear ends, whereupon it will follow the usual trajectory, varying of course with the speed and elevation at which the aeroplane is traveling, and also according to its angle 80 of travel with respect to the horizontal. Thus by raising the forward end of the aeroplane, the trajectory will be much longer than would occur if the forward end of the aeroplane were pointed downwardly with 85 respect to the horizontal. This point should be taken into consideration during the launching together with the approximate speed. 90

As soon as the torpedo strikes the water, 95 the bands holding the cap and shield in place will almost instantly lose their tensile strength and owing to the weight of the shield and the almost neutral buoyancy of the torpedo an immediate separation will 100 occur. The torpedo will immediately right itself and seek its proper level according to its setting and will continue its journey by reason of its gyroscopic control in substantially the same vertical plane as that of its 105 launching trajectory.

Owing to the fact that the height at which the torpedo is launched varies to a considerable extent, with a consequent variation in time of flight, it is desirable that 110 means not herein shown should be provided for starting the engine of the torpedo immediately upon submengence, thereby to avoid racing of the engine during its downward flight and sudden subsequent retardation of the same on submengence. 115

From the above it will be seen that the present invention provides a simple, practical and automatic means for shifting the center of gravity of the torpedo to the desired location to permit practical aerial launching, and subsequent separation of the attachment whereby the center of gravity is restored to the proper relative position to enable the torpedo to continue its customary 120 submarine travel.

Without further analysis, the foregoing will so fully reveal the gist of this invention that others can by applying current knowledge readily adapt it for various applica- 125 130

tions without omitting certain features that, from the standpoint of the prior art, fairly constitute essential characteristics of the generic or specific aspects of this invention, 5 and therefore such adaptations should and are intended to be comprehended within the meaning and range of equivalency of the following claims.

I claim as my invention:—

- 10 1. An attachment for torpedoes comprising a means for shifting its center of gravity, including a hollow cap and a substantially U-shaped extension, semi-soluble means for attaching said member to a torpedo and 15 adapted to rupture when the torpedo is submerged to release said member therefrom.
2. An attachment for aerial torpedoes comprising a weighted member and semi-soluble means for attaching the same to the 20 torpedo for shifting its center of gravity.
3. An attachment for torpedoes comprising a weighted member and means for attaching the same to the torpedo for shifting its center of gravity before submerging and 25 automatically restoring the same immediately after submerging.
4. An attachment for aerial torpedoes comprising a false nose or cap, and semi-soluble means for attaching said nose to the 30 forward end of a torpedo for automatically shifting the center of gravity immediately on submerging whereby the same may be practically launched from aeroplanes.
5. In combination with a submarine tor- 35 pedo, an attachment therefor comprising a cap adapted to fit over the forward end of a torpedo, and means adapted to hold said cap in place and automatically release the cap when the torpedo is submerged.
- 40 6. In combination with a submarine torpedo, a hollow weighted cap adapted to fit over the forward end thereof to shift the center of gravity forwardly and downwardly, and means for securing said cap on the torpedo adapted to automatically release the cap immediately when the torpedo is submerged to restore the center of gravity to its original position.
- 45 7. In combination with a submarine tor- 50 pedo, a member including a hollow cap

adapted to fit over the forward end thereof to shift the center of gravity forwardly and downwardly, and means for securing said cap on the torpedo adapted to automatically release the cap when the torpedo is submerged to restore the center of gravity to its original position, said means being made of fibrous material. 55

8. In combination with a submarine torpedo, a member including a hollow cap 60 adapted to fit over the forward end thereof to shift the center of gravity forwardly and downwardly, and means for securing said cap on the torpedo adapted to automatically release the cap when the torpedo is submerged to restore the center of gravity to its 65 original position, said means including a plurality of semi-soluble strips of material securing the cap to the body of the torpedo, and means carried by the cap adapted to cut 70 said strips when the torpedo is submerged to assist in freeing the cap therefrom.

9. In combination with a torpedo, a hollow cap adapted to fit over the nose of said torpedo, a shield connected with the under 75 side of the cap whereby the center of gravity of the torpedo is shifted forwardly and downwardly, and means for securing said cap and shield in place and adapted to automatically release the cap and shield as 80 soon as the torpedo is submerged.

10. In combination with a torpedo, a semi-spherical hollow cap adapted to fit over the nose of said torpedo, a shield connected with the under side of the cap whereby the 85 center of gravity of the torpedo is shifted forwardly and downwardly, means for securing said cap and shield in place and adapted to automatically release the cap and shield as soon as the torpedo is submerged, 90 said means including a plurality of strips of blotting paper extending between the cap and shield and the body of the torpedo, and means adapted to cut the strips as the cap and shield leave the torpedo after submer- 95 gence.

Signed at Washington this 29th day of September, 1917.

GEORGES J. N. CARPENTIER.
